MIRROR BACKING AND SUPPORT

Martin J. Maley, Detroit, Mich., assignor to Pittsburgh Plate Glass Company, Allegheny County, Pa., a corporation of Pennsylvania

Application September 21, 1935, Serial No. 41,619

2 Claims. (Cl. 88—97)

This invention relates to a new construction for supporting mirrors and more particularly to metallic structures for securing mirrors in substantially vertical position. The principal object of my invention is to produce a construction of the character designated which will afford protection for the silvered face of the mirror. Another object of the present invention is to provide a strong, durable and inexpensive support for mirrors which will not detract from the appearance of the finished installation or require mutilation of the mirrors. A further object of this invention is to furnish a support in which a mirror may be secured in or removed from position easily and quickly.

Heretofore the positioning of mirrors on store walls has been accompanied by many difficulties. In most cases, mirrors have been installed in recesses provided in the wainscoting material during construction. An installation of this type is more or less permanent in nature, the mirror being held in place by metallic mouldings. Other methods of setting mirrors include the use of ornamental bolts passing through the mirror itself and the use of a mastic preparation. In each case it is necessary to employ special tools, equipment, materials and workmen for the original placement. Accordingly, when it is required to move or replace a mirror, an ordinary glazier or mechanic would not be able to accomplish the task. Furthermore, in none of the structures, of which I am aware, is there provided a positive insulating space to protect and delay deterioration of the silvered surface of the mirror.

This invention provides an entirely new method of positioning mirrors and eliminates many of the disadvantages arising from the prior methods. For example, using my structure, a broken mirror can be very easily replaced by an ordinary workman employing only a small hammer.

A preferred form of my invention is shown in the accompanying drawing, wherein:

Figure 1 is a plan view of a structure embodying my invention; Figure 2 is a sectional view taken on line II—II of Figure 1; Figure 3 is a plan view of a modified form of construction; and Figure 4 is a partial sectional view of a further modification.

Referring to the drawing, the mirror support comprises a sheet metal backing plate 1 provided with a plurality of openings 2 adapted to receive screws 3, by means of which the entire structure is positioned in a desired location. The screws 3 enter wooden supports 4 which are secured to the basic wall construction 5 by any suitable

means. The wooden supports 4 are of sufficient size to extend beyond the surface of structural glass sheets or tile slabs 6, thereby providing positive clearance by the mirror support of said glass or tile surface. The structural glass sheets 5 or tile slabs 6, so placed as to lie under a considerable portion of the mirror support when it is installed, are secured to the basic wall construction 5 by means of a mastic preparation 7. Cushioning strips 8 and 9 of felt or other resilient material are secured to both faces of the plate 1 adjacent the periphery thereof. Spaced supporting clips 10 of hook shape are fixed at the periphery of the plate, bearing equally the weight of the mirror 11. The mirror 11 is held in vertical position upon the structure by means of an adjustable clamping member 12 of hook shape. Said clamping member 12 is provided with a slot 13 permitting vertical adjustment thereof. A rivet 14 is disposed through the slot 13 adjustably securing the clamping member 12 to the metal plate 1. Guards 15 are placed on both sides of this clamping member 12, preventing side play thereof.

In Figure 3, the backing plate 1 is rectangular in shape and a plurality of the adjustable clamping members 12 are secured to its top edge, providing more positive means of positioning the large size mirror 11. Figure 4 shows a modification in which the cushioning strips 8 and 9 are replaced by a cotton-filled rubber welt 16 attached to the backing plate 1 by rivets 17.

It will be readily apparent from the above description that the spacer strips 8 and 9, or in like manner, the welt 16 serve to insulate the metal backing plate 1 from the glass or tile surface 6 of the wall 5 upon which said metal plate is mounted. In addition, through the same medium, an air space is provided between the metal plate and the mirror. Accordingly there is no metal in contact with the silvered face of the mirror which might damage the reflecting surface. Furthermore, there is no possibility of damaging the reflecting surface while placing the mirror in position.

It will be understood that further modifications of this structure may be made without departing from the spirit of my invention. Therefore I do not wish to be limited to the specific form disclosed other than as defined in the appended claims.

What I claim is:

1. A mirror and wall assembly comprising a wall having a surface coating secured thereupon, an opening in said surface coating, supporting

members rigidly secured to the wall within the opening, a metallic backing plate removably secured to said supporting members by means operable from the front of the plate, said backing plate when in position upon the supporting members being spaced from the surface coating of the wall, a mirror removably secured to the backing plate by a plurality of clamping means disposed around said backing plate and operable from the front thereof when the mirror is in position, said mirror and plate being proportioned to con-

ceal the opening in the surface coating of the wall, and a strip of yieldable, resilient material secured adjacent the periphery of the backing plate to hold said plate and mirror in spaced relation.

2. An assembly as defined in claim 1 in which means are provided to separate the marginal edge of said backing plate from the surface coating of the wall.

MARTIN J. MALEY. 10
